RADIAL PUMP OR MOTOR

Elek K. Benedek, Cleveland, Ohio, assignor, by
mesne assignments, to Midland Machine Cor-
poration, a corporation of Illinois

Application November 6, 1940, Serial No. 364,585

20 Claims.

(CL. 103—161)

This invention relates to hydraulic pumps or motors, and more particularly to hydraulic pumps or motors of the type including a plurality of radially disposed piston and cylinder assemblies.

Machines of the kind referred to, in general, comprise a stationary pintle provided with fluid transfer passages or conduits, a cylinder barrel rotatable about the pintle and being formed with a plurality of radially disposed, circumferentially spaced cylinders adapted to have valved communication with the pintle conduits, pistons in the cylinders, and means for effecting reciprocation of the pistons relatively to the respective cylinders when the cylinder barrel is rotated. Because of their substantially continuous, positive pressure discharge characteristics, such pumps lately have found wide application in various fields, use for driving machine tools and hydraulic presses being representative examples of useful applications.

Pumps of this general class heretofore proposed most commonly have included a single set of circumferentially deployed radial piston and cylinder assemblies. For such machines to deliver fluid at high volumetric rates without operating at prohibitive speeds, it has been necessary to use large pistons and cylinders, increasing the diameter of the rotating assemblies and surrounding parts so that inordinate centrifugal forces have been produced, resulting in high thrust bearing pressures and rapid wear, and necessitating inconveniently large overall radial dimensions.

To overcome these difficulties it heretofore has been proposed to provide a plurality, e. g., two sets of piston and cylinder assemblies spaced from each other longitudinally of the pump pintle and to operate the pistons in pairs, each pair including a piston of each of the two sets of assemblies. In this way provision may be made for discharge of fluid at high volumetric rates without the use of very large pistons and cylinders, and consequently without unduly large diameter of rotative assemblies. The present invention has to do with improvements in the construction and assembling of pumps or motors of this particular kind.

An object of the invention is to provide a pump or motor of the class referred to in which the construction and relative arrangement of the parts enables the incorporation in a compact machine of a plurality of sets of spaced piston and cylinder assemblies.

Another object is to provide a pump or motor of the character stated of such construction as 55

to facilitate manufacturing and assembling of the parts.

Another object is to provide simple and efficient means for transmitting thrust to the reciprocable elements of the piston and cylinder assemblies.

A further object is to provide a compact and durable organization of parts for transmitting thrust to pistons of two spaced sets of piston and cylinder assemblies in which the assemblies of one of the sets are staggered circumferentially with respect to the assemblies of the other set. Other objects will become apparent from a reading of the following detailed description, the appended claims and the accompanying drawings, in which:

Figure 1 is a longitudinal horizontal sectional view of a pump or motor embodying the invention, the section being taken on the line 1—1 of

Figure 2;

Figure 2 is a transverse vertical sectional view taken on the line 2—2 of Figure 1;

Figure 3 is a fragmentary sectional view taken on the line 3—3 of Figure 1;

Figure 4 is a detailed sectional view taken on the line 4—4 of Figure 1;

Figure 5 is another detailed sectional view taken on the line 5—5 of Figure 1;

Figure 6 is a fragmentary developed sectional view taken on the curved line 6—6 of Figure 2;

Figure 7 is a horizontal sectional view similar to Figure 1 but showing a modified construction;

Figure 8 is a transverse vertical section taken on the line 8—8 of Figure 7;

Figure 9 is a fragmentary sectional view taken on the line 9—9 of Figure 7; and

Figure 10 is a fragmentary developed sectional view taken on the curved line 10—10 of Figure 8.

40 The embodiment disclosed in Figures 1 to 6, inclusive, comprises a casing 1 including two end plate sections 2 and 3 and an intervening ring section 4 secured between the end plate sections by means of screws 5. The opposed inner faces

45 of the peripheral portions of the end plates 2 and 3 are recessed to provide shoulders 6 and 7 which serve accurately to locate the end plates 2 and 3 and the ring member 4 in assembled relation. A hardened stationary pintle 9 has a

50 press fit in a bore 10 formed in an axial hub-like extension 11 of the end plate section 2. The pintle is formed with a reduced diameter portion 12 on which a cylinder barrel unit generally designated 13 is journaled by roller bearings 14 for rotation about the pintle axis. The end

plate section 1 is formed with a hub extension 15 in which is mounted an anti-friction ball bearing assembly generally designated 16, the outer race 17 of which is held in place by an end cap 18 secured to the hub portion 15 by screws 19. The inner race 20 of the bearing assembly 16 is mounted on an inner end portion 21 of a drive shaft generally designated 22. At the extreme inner end of the shaft 21 is an enlarged flange 23 providing a shoulder 24 against which the inner ball race 20 is clamped by a nut 25 engaging a threaded portion 26 of the shaft 22. The shaft flange 23 is secured to the cylinder barrel by means of screws 27. The shaft 22 may be used to impart positive driving effort to the cylinder barrel unit 13 if the machine is to be used as a pump, and may be used to transmit power from the rotating cylinder barrel unit 13 to external apparatus to be driven when the machine is to be used as a hydraulic motor. To facilitate manufacturing and assembling of the machine, the cylinder barrel unit 13 is formed in two axially separable sections 28 and 28' having a mortise joint as at 29 and being secured together by bolts 30.

The cylinder barrel unit is formed with two axially spaced sets, generally designated A and B, of radially disposed, circumferentially deployed, piston and cylinder assemblies. The set A of piston and cylinder assemblies, shown at the right in Figure 1 and also shown in Figure 2, includes a plurality of circumferentially spaced cylinders 31 formed in the cylinder barrel section 28 and respectively communicating with ports 32 in turn adapted to have valved communication with pintle cut-outs or ports 33 having constant communication with bored pintle passages 34. The passages 34 communicate with combined inlet and outlet openings on opposite sides of the pintle and one, 35, of which is shown at the left in Figure 1. Pistons 36 are mounted respectively for reciprocation in the cylinders 31. When the cylinder barrel and pistons are rotated, the pistons will be reciprocated relatively to the associated cylinders in a manner to be described later, and the valved intake and discharge of fluid through the opening 35, the passages 34, the cut-out ports 33, and the cylinder end ports 32 will take place in a manner well understood in the art. The other set B of piston and cylinder assemblies is spaced axially to the left (as viewed in Figure 1) of the set A and includes a plurality of cylinders 31' formed in the cylinder barrel section 28' and in which pistons 36' are mounted for reciprocation to take in and discharge fluid through end ports 32', pintle cut-out passages 33', the bored pintle passages 34, and the pintle intake and outlet openings 35.

Individual piston and cylinder assemblies of the set A are paired, respectively, in parallelism with individual piston and cylinder assemblies of the set B, and means are provided for reciprocating the paired pistons of the two sets in unison. The pistons 36 of the set A are formed with crossheads 37 mounted to slide in guides formed in a flange 38 integral with the cylinder barrel section 28. Similarly, the pistons 36' of the set B are formed with crossheads 37' slideable in guides formed in a flange 38' integral with the cylinder barrel section 28'. The crossheads 37 and 37' of the sets A and B are paired, and are formed respectively with bores equipped with bushings 39-39'. Thrust-transmitting cross pins 40 and 40' are journaled respectively in the bushings 39 and 39'. Pins 40 and 40' 75

associated respectively with paired pistons of the sets A and B are aligned with their inner ends in face-to-face relation and are held in place by retaining rings 41 and 41'.

For transmitting thrust to and reciprocating the pins and the pistons of both sets A and B, reactance means surrounding the piston and cylinder assemblies of both sets A and B is provided with annular tracks engaged by the pins in three zones spaced from each other longitudinally of the pintle axis; and means are provided for mounting the three tracks of the reactance means eccentrically with respect to the pintle axis, so that, as the cylinder barrel, the pistons, and the pins rotate about the pintle axis, the engagement of the pins simultaneously with the three eccentrically disposed tracks will move the pistons in to their respectively associated cylinders. The reactance means includes a shiftable, non-rotating reactance stator comprising end sections 42 and 42' secured to a central ring section 43 by means of screws 44-44'. The ring section 43 is formed with flat pads 45 mounted to slide on pads 46 formed on the inner surface of the casing ring 4 so as to mount the stator for shifting movement to vary its eccentricity with respect to the pintle axis. Rods 47 secured to the central ring section 43 of the stator extend through the casing and are adapted to be connected to suitable handles or mechanism for shifting the stator. It is usual to mount the reactance stator in pumps of this class so that it may shift to vary its eccentricity, and, hence, the rate of discharge of the pump, but it will be understood that the invention may be embodied in rotary radial pumps wherein the reactance stator is mounted in a fixed eccentric position.

The stator end sections 42 and 42' are formed, respectively, with bearing race seats 48 and 48' which respectively receive the outer races of bearing assemblies generally designated 49 and 49'. The bearing assemblies 49 and 49' serve anti-frictionally to mount a rotary reactance member 50 comprising end plate sections 51 and 51' secured by screws 52 and 52', respectively, to a hardened central ring section 53.

The end plate sections 51 and 51' are formed respectively with annular tracks 54 and 54' disposed in the radial planes or zones of the outer end of the pins 40 and 40'. Outwardly beyond the tracks 54 and 54' the end plate sections 51 and 51' are formed, respectively, with outer radial surfaces 55 and 55' which lie alongside and serve to guide the outer portions of the crossheads 37 and 37'. Inwardly of the annular tracks 54 and 54' the end plate sections 51 and 51' are formed, respectively, with inner radial surfaces 56 and 56' which lie alongside the extreme end portions of the pins 40-40' with working clearance between the radial surfaces and the flat pin ends. The central section 53 of the rotary reactance 50 is formed with an inwardly extending, centrally disposed flange 57 located between the radial planes of the sets A and B. The inner face of the flange 57 constitutes a track 58 upon which the inner ends of the pins 40-40' are adapted to roll. Opposed, outwardly directed, radial faces 59 and 59' of the track flange 57 lie alongside and respectively guide the outer portions of the piston crossheads 37 and 37'.

When the machine is operated as a pump, the centrifugal force acting on the pins 40-40', pistons 36 and 36', and associated crossheads tends to move them outwardly with respect to their

cylinders so as to perform suction strokes. To assist in this outward movement, and, more particularly, to maintain the pins in engagement with the reactance tracks 58, 54, and 54' when the pump is at rest and while it is being brought up to operating speed, floating return-thrust-transmitting rings 60 and 60' are disposed respectively within the circles defined generally by the outer end portions of the pins 40-40'. The rings 60 and 60' are supported radially solely by their engagement with the pins 40-40', and are confined against movement longitudinally of the piston by the piston crossheads and the adjacent inner radial surfaces 56 and 56' of the reactance rotor end plate sections 51 and 51'. Another return-thrust-transmitting ring 61 is disposed between the sets A and B and in the zone of the middle track 59. This ring also is supported radially solely by its engagement with the pins 40-40'. It is held against shifting axially of the pintle by engagement with adjacent faces of the crossheads 37 and 37'.

In operation, when the reactance stator and the rotary reactance member 50 carried thereby are shifted to be eccentric to the pintle axis, rotation of the cylinder barrel, the pistons of both sets A and B, and the pins will cause the pins 40-40' to roll in three zones on the tracks 54, 54', and 58; and the pins and the pistons of both sets A and B will be reciprocated radially to effect valved intake and discharge of fluid through the ports and passages previously described.

The parts of the simple and rugged construction described above are adapted for economical manufacture and quick assembling and disassembling for cleaning or servicing. The simple thrust-transmitting pins of uniform diameter can be made from bar or tube stock and finished in mass production by centerless grinding.

In the modified embodiment shown in Figures 7 to 10, inclusive, the construction is generally similar to that described above. It differs specifically therefrom only as is described below, it being understood that parts of the modified form not specifically referred to are essentially the same as corresponding parts of the embodiment shown in Figures 1 to 6, inclusive.

In the modified embodiment the sets A and B of piston and cylinder assemblies are staggered circumferentially with respect to each other so as to permit the pins 40 of the section A to overlap respectively and intervene between adjacent pins 40' of the section B between the sets A and B. This makes it possible to decrease the width of the reactance rotor indicated generally at 50a. The rotor comprises end sections 51 and 51' which are the same as the corresponding sections in the reactance rotor shown in Figures 1 to 6, inclusive, and a central ring section 53a interposed between the end sections 51 and 51'. The central ring section 53a is narrower than the corresponding ring section 53 in the form shown in Figures 1 to 6, inclusive. Similarly the flange 57a and middle track 58a are more narrow. The operation of the modified embodiment is similar to the operation of the embodiment shown in Figures 1 to 6, inclusive, with the exception that the staggering of the sets of piston and cylinder assemblies makes for a more uniform flow of fluid with consequent lessening of the magnitude of pulsations and for more even distribution of the piston load about the periphery of the reactance.

The construction shown herein for the purposes of illustration embody the invention in its

now preferred forms, but it will be apparent that some changes in the construction and relative arrangement of the parts may be made without departing from the invention as defined in the claims.

I claim:

1. In a rotary hydraulic pump or motor, two sets of rotatable radial piston and cylinder assemblies, each set including a plurality of circumferentially deployed piston and cylinder assemblies, said assemblies each comprising a piston element and a cooperating cylinder element, one element of each assembly being reciprocable radially relative to the axis of rotation of said assemblies and said sets of assemblies being spaced from each other longitudinally of the axis of rotation; thrust-transmitting pins respectively individually journaled in the reciprocable elements of both sets and extending parallel to said axis of rotation, the pins journaled in the reciprocable elements of one set being independent of the pins journaled in the reciprocable elements of the other set; and a reactance member for effecting reciprocation of all said reciprocable elements in response to rotation of said assemblies, said reactance member including a track eccentric to said axis of rotation, being located between said sets of assemblies, and being rollingly and independently engaged by all of said pins of both said sets of assemblies.

2. In a rotary hydraulic pump or motor, two sets of rotatable radial piston and cylinder assemblies, each set including a plurality of circumferentially deployed piston and cylinder assemblies, said assemblies each comprising a piston element and a cooperating cylinder element, one element of each assembly being reciprocable radially relative to the axis of rotation of said assemblies and said sets of assemblies being spaced from each other longitudinally of the axis of rotation; thrust-transmitting pins respectively individually journaled in the reciprocable elements of both sets and extending parallel to said axis of rotation and projecting beyond the respectively associated reciprocable elements, the pins journaled in the reciprocable elements of one set being independent of the pins journaled in the reciprocable elements of the other set; and a reactance member for effecting reciprocation of all said reciprocable elements in response to rotation of said assemblies, said reactance member including a track eccentric to said axis of rotation, being located between said sets of assemblies, and being rollingly and independently engaged by projecting portions of all of said pins of both said sets of assemblies.

3. In a rotary hydraulic pump or motor, two sets of rotatable radial piston and cylinder assemblies, each set including a plurality of circumferentially deployed piston and cylinder assemblies, said assemblies each comprising a piston element and a cooperating cylinder element, one element of each assembly being reciprocable radially relative to the axis of rotation of said assemblies and said sets of assemblies being spaced from each other longitudinally of the axis of rotation, thrust-transmitting pins respectively individually journaled in the reciprocable elements of both sets and extending parallel to said axis of rotation and projecting beyond the respectively associated reciprocable elements, the pins journaled in the reciprocable elements of one set being independent of the pins journaled in the reciprocable elements of the other set; and

a reactance member for effecting reciprocation of all said reciprocable elements in response to rotation of said assemblies, said reactance member including a track intervening said two sets of piston and cylinder assemblies and being eccentric to said axis of rotation, said track being rollingly and independently engaged by projecting portions of all of said pins of both said sets of assemblies.

4. In a rotary hydraulic pump or motor, two sets of rotatable radial piston and cylinder assemblies, each set including a plurality of circumferentially deployed piston and cylinder assemblies, said assemblies each comprising a piston element and a cooperating cylinder element, one element of each assembly being reciprocable radially relative to the axis of rotation of said assemblies and said sets of assemblies being spaced from each other longitudinally of the axis of rotation; thrust-transmitting pins respectively individually journaled in the reciprocable elements of both sets and extending parallel to said axis of rotation and projecting beyond the respectively associated reciprocable elements, the pins journaled in the reciprocable elements of one set being independent of the pins journaled in the reciprocable elements of the other set; and a reactance member for effecting reciprocation of all said reciprocable elements in response to rotation of said assemblies, said reactance member including a single continuous track intervening said two sets of piston and cylinder assemblies and being eccentric to said axis of rotation, said track being rollingly and independently engaged by projecting portions of all of said pins of both said sets of assemblies.

5. In a rotary hydraulic pump or motor, two sets of rotatable radial piston and cylinder assemblies, each set including a plurality of circumferentially deployed piston and cylinder assemblies, said assemblies each comprising a piston element and a cooperating cylinder element, one element of each assembly being reciprocable radially relative to the axis of rotation of said assemblies and said sets of assemblies being spaced from each other longitudinally of the axis of rotation; thrust-transmitting pins respectively individually journaled in the reciprocable elements of both sets and extending parallel to said axis of rotation, said pins respectively having opposite end portions projecting beyond their associated reciprocable elements, the pins journaled in the reciprocable elements of one set being independent of the pins journaled in the reciprocable elements of the other set; and a reactance member for effecting reciprocation of all said reciprocable elements in response to rotation of said assemblies, said reactance member including three spaced tracks similarly eccentric to said axis of rotation, the middle track intervening said sets of assemblies and being rollingly and independently and simultaneously engaged by projecting portions of said pins of both said sets of assemblies which extend between said sets of assemblies, one of the end tracks being rollingly and simultaneously engaged by the other projecting portions of pins associated with one set of assemblies and the other end track being rollingly and simultaneously engaged by the other projecting portions of pins associated with the other set of assemblies.

6. In a rotary hydraulic pump or motor, two sets of rotatable radial piston and cylinder assemblies, each set including a plurality of circumferentially deployed piston and cylinder as-

semblies, said assemblies each comprising a piston element and a cooperating cylinder element, one element of each assembly being reciprocable radially relative to the axis of rotation of said assemblies and said sets of assemblies being spaced from each other longitudinally of the axis of rotation; thrust-transmitting pins respectively individually journaled in the reciprocable elements of both sets and extending parallel to said axis of rotation and projecting beyond the respectively associated reciprocable elements, the pins journaled in the reciprocable elements of one set being independent of the pins journaled in the reciprocable elements of the other set; and a reactance means for effecting reciprocation of all said reciprocable elements in response to rotation of said assemblies, said reactance means including a relatively fixed working-thrust transmitting track eccentric to said axis of rotation and being rollingly and independently engaged by projecting portions of all said pins of both said sets of assemblies, and a relatively floating ring providing a suction-thrust transmitting track also rollingly engaged by the same projecting portions of said pins, both said tracks being disposed between said sets of assemblies.

7. In a rotary hydraulic pump or motor, a rotatable cylinder barrel unit comprising two sections adapted to be assembled and separated in a direction longitudinally of the axis of rotation of said unit, and means for maintaining said sections in assembled relation, each section being formed with a set of radial, circumferentially deployed cylinders, the two sets of cylinders being mutually spaced longitudinally of said axis of rotation; pistons reciprocable in the cylinders of each set respectively; thrust-transmitting pins respectively individually journaled in the pistons associated with each set of cylinders and extending parallel to said axis of rotation and projecting beyond the respectively associated pistons, the pins journaled in the pistons of one set being independent of the pins journaled in the pistons of the other set; and a reactance member for effecting reciprocation of all said pistons in response to rotation of said cylinder barrel, said reactance member including a track intervening said two sets of pistons and being eccentric to said axis of rotation, said track being rollingly and independently engageable by projecting portions of said pins of both said sets of pistons.

8. In a rotary hydraulic pump or motor, a rotatable cylinder barrel unit comprising two sections adapted to be assembled and separated in a direction longitudinally of the axis of rotation of said unit, means providing a mortise joint between said sections for aligning them, and means for maintaining said sections in assembled relation, each section being formed with a set of radial, circumferentially deployed cylinders, the two sets of cylinders being mutually spaced longitudinally of said axis of rotation; pistons reciprocable in the cylinders of each set respectively; thrust-transmitting pins respectively individually journaled in the pistons associated with each set of cylinders and extending parallel to said axis of rotation and projecting beyond the respectively associated pistons, the pins journaled in the pistons of one set being independent of the pins journaled in the pistons of the other set; and a reactance member for effecting reciprocation of all said pistons in response to rotation of said cylinder barrel, said reactance member including a track intervening said two sets of pistons and being eccentric to said axis of rotation, said track

being rollingly and independently engageable by projecting portions of said pins of both said sets of pistons.

9. In a rotary hydraulic pump or motor, two sets of rotatable radial piston and cylinder assemblies, each set including a plurality of circumferentially deployed piston and cylinder assemblies, said assemblies each comprising a piston element and a cooperating cylinder element, one element of each assembly being reciprocable radially relative to the axis of rotation of said assemblies and said sets of assemblies being spaced from each other longitudinally of the axis of rotation, individual assemblies of one of said sets being paired respectively in parallelism with individual assemblies of the other of said sets; thrust-transmitting pins respectively individually journaled in the reciprocable elements of both sets and extending parallel to said axis of rotation, the pins journaled in the reciprocable elements of one set being independent of the pins journaled in the reciprocable elements of the other set; and a reactance member for effecting reciprocation of all said reciprocable elements in response to rotation of said assemblies, said reactance member including a track eccentric to said axis of rotation and being rollingly and independently engaged by all of said pins of both said sets of assemblies.

10. In a rotary hydraulic pump or motor, two sets of rotatable radial piston and cylinder assemblies, each set including a plurality of circumferentially deployed piston and cylinder assemblies, said assemblies each comprising a piston element and a cooperating cylinder element, one element of each assembly being reciprocable radially relative to the axis of rotation of said assemblies and said sets of assemblies being spaced from each other longitudinally of the axis of rotation, individual assemblies of one of said sets being paired respectively in parallelism with individual assemblies of the other of said sets; thrust-transmitting pins respectively individually journaled in the reciprocable elements of both sets and extending parallel to said axis of rotation and projecting beyond the respectively associated reciprocable elements, the pins journaled in the reciprocable elements of one set being independent of the pins journaled in the reciprocable elements of the other set; and a reactance member for effecting reciprocation of all said reciprocable elements in response to rotation of said assemblies, said reactance member including a track eccentric to said axis of rotation and being rollingly and independently engaged by projecting portions of all of said pins of both said sets of assemblies.

11. In a rotary hydraulic pump or motor, two sets of rotatable radial piston and cylinder assemblies, each set including a plurality of circumferentially deployed piston and cylinder assemblies, said assemblies each comprising a piston element and a cooperating cylinder element, one element of each assembly being reciprocable radially relative to the axis of rotation of said assemblies and said sets of assemblies being spaced from each other longitudinally of the axis of rotation, individual assemblies of one of said sets being paired respectively in parallelism with individual assemblies of the other of said sets; thrust-transmitting pins respectively individually journaled in the reciprocable elements of both sets and extending parallel to said axis of rotation and projecting beyond the respectively associated reciprocable elements, the pins jour-

naled in the reciprocable elements of one set being independent of the pins journaled in the reciprocable elements of the other set; and a reactance member for effecting reciprocation of all said reciprocable elements in response to rotation of said assemblies, said reactance member including a track intervening said two sets of piston and cylinder assemblies and being eccentric to said axis of rotation, said track being rollingly and independently engaged by projecting portions of all of said pins of both said sets of assemblies.

12. In a rotary hydraulic pump or motor, two sets of rotatable radial piston and cylinder assemblies, each set including a plurality of circumferentially deployed piston and cylinder assemblies, said assemblies each comprising a piston element and a cooperating cylinder element, one element of each assembly being reciprocable radially relative to the axis of rotation of said assemblies and said sets of assemblies being spaced from each other longitudinally of the axis of rotation, individual assemblies of one of said sets being paired respectively in parallelism with individual assemblies of the other of said sets; thrust-transmitting pins respectively individually journaled in the reciprocable elements of both sets and extending parallel to said axis of rotation, said pins respectively having opposite end portions projecting beyond their associated reciprocable elements, the pins journaled in the reciprocable elements of one set being independent of the pins journaled in the reciprocable elements of the other set; and a reactance member for effecting reciprocation of all said reciprocable elements in response to rotation of said assemblies, said reactance member including three spaced tracks similarly eccentric to said axis of rotation, the middle track intervening said sets of assemblies and being rollingly and independently and simultaneously engaged by projecting portions of said pins which extend between said sets of assemblies, the pins associated with the assemblies of each pair of assemblies being aligned with each other and being in end-to-end relation over said middle track, one of the end tracks being rollingly and simultaneously engaged by the other projecting portions of pins associated with one set of assemblies and the other end track being rollingly and simultaneously engaged by the other projecting portions of pins associated with the other set of assemblies.

13. In a rotary hydraulic pump or motor, a rotatable cylinder barrel having formed therein two sets of cylinders, each set comprising a plurality of radial, circumferentially deployed cylinders lying in a common plane transverse to the axis of rotation, the two sets being spaced from each other longitudinally of the axis of rotation of said barrel, individual cylinders of one of said sets being paired respectively in parallelism with individual cylinders of said other of said sets, thrust-transmitting pins respectively individually journaled in the pistons associated with each set of cylinders and extending parallel to said axis of rotation and projecting beyond the respectively associated pistons, the pins journaled in the pistons of one set being independent of the pins journaled in the pistons of the other set; and a reactance member for effecting reciprocation of all said pistons in response to rotation of said cylinder barrel, said reactance member including a track intervening said two sets of pistons and being eccentric to said axis of rotation, said track being rollingly and inde-

pendently engageable by projecting portions of said pins of both said sets of pistons, the pins associated with the pistons of each pair of pistons being aligned with each other and being in end-to-end relation over said track.

14. In a rotary hydraulic pump or motor, two sets of rotatable radial piston and cylinder assemblies, each set including a plurality of circumferentially deployed piston and cylinder assemblies, said assemblies each comprising a piston element and a cooperating cylinder element, one element of each assembly being reciprocable radially relative to the axis of rotation of said assemblies and said sets of assemblies being spaced from each other longitudinally of the axis of rotation, the assemblies of one of said sets being circumferentially staggered with respect to the assemblies of the other of said sets; thrust-transmitting pins respectively individually journaled in the reciprocable elements of both sets and extending parallel to said axis of rotation, the pins journaled in the reciprocable elements of one set being independent of the pins journaled in the reciprocable elements of the other set; and a reactance member for effecting reciprocation of all said reciprocable elements in response to rotation of said assemblies, said reactance member including a track eccentric to said axis of rotation and being rollingly and independently engaged by all of said pins of both said sets of assemblies.

15. In a rotary hydraulic pump or motor, two sets of rotatable radial piston and cylinder assemblies, each set including a plurality of circumferentially deployed piston and cylinder assemblies, said assemblies each comprising a piston element and a cooperating cylinder element, one element of each assembly being reciprocable radially relative to the axis of rotation of said assemblies and said sets of assemblies being spaced from each other longitudinally of the axis of rotation, the assemblies of one of said sets being circumferentially staggered with respect to the assemblies of the other of said sets; thrust-transmitting pins respectively individually journaled in the reciprocable elements of both sets and extending parallel to said axis of rotation and projecting beyond the respectively associated reciprocable elements, the pins journaled in the reciprocable elements of one set being independent of the pins journaled in the reciprocable elements of the other set; and a reactance member for effecting reciprocation of all said reciprocable elements in response to rotation of said assemblies, said reactance member including a track eccentric to said axis of rotation and being rollingly and independently engaged by projecting portions of all of said pins of both said sets of assemblies.

16. In a rotary hydraulic pump or motor, two sets of rotatable radial piston and cylinder assemblies, each set including a plurality of circumferentially deployed piston and cylinder assemblies, said assemblies each comprising a piston element and a cooperating cylinder element, one element of each assembly being reciprocable radially relative to the axis of rotation of said assemblies and said sets of assemblies being spaced from each other longitudinally of the axis of rotation, the assemblies of one of said sets being circumferentially staggered with respect to the assemblies of the other of said sets; thrust-transmitting pins respectively individually journaled in the reciprocable elements of both sets

and extending parallel to said axis of rotation and projecting beyond the respectively associated reciprocable elements, the pins journaled in the reciprocable elements of one set being independent of the pins journaled in the reciprocable elements of the other set; and a reactance member for effecting reciprocation of all said reciprocable elements in response to rotation of said assemblies, said reactance member including a track intervening said two sets of piston and cylinder assemblies and being eccentric to said axis of rotation, said track being rollingly and independently engaged by projecting portions of all of said pins of both said sets of assemblies.

17. In a rotary hydraulic pump or motor, two sets of rotatable radial piston and cylinder assemblies, each set including a plurality of circumferentially deployed piston and cylinder assemblies, said assemblies each comprising a piston element and a cooperating cylinder element, one element of each assembly being reciprocable radially relative to the axis of rotation of said assemblies and said sets of assemblies being spaced from each other longitudinally of the axis of rotation, the assemblies of one of said sets being circumferentially staggered with respect to the assemblies of the other of said sets, thrust-transmitting pins respectively individually journaled in the reciprocable elements of both sets and extending parallel to said axis of rotation, said pins respectively having opposite end portions projecting beyond their associated reciprocable elements, the pins journaled in the reciprocable elements of one set being independent of the pins journaled in the reciprocable elements of the other set; and a reactance member for effecting reciprocation of all said reciprocable elements in response to rotation of said assemblies, said reactance member including three spaced tracks similarly eccentric to said axis of rotation, the middle track intervening said sets of assemblies and being rollingly and independently and simultaneously engaged by projecting portions of said pins of both said sets of assemblies which extend between said sets of assemblies, the pins associated with the assemblies of one of said sets overlapping the pins associated with the assemblies of said other set parallel to said axis of rotation, one of the end tracks being rollingly and simultaneously engaged by the other projecting portions of pins associated with one set of assemblies and the other end track being rollingly and simultaneously engaged by the other projecting portions of pins associated with the other set of assemblies.

18. In a rotary hydraulic pump or motor, a rotatable cylinder barrel unit comprising two sections adapted to be assembled and separated in a direction longitudinally of the axis of rotation of said unit, and means for maintaining said sections in assembled relation, each section being formed with a set of radial, circumferentially deployed cylinders, the two sets of cylinders being mutually spaced longitudinally of said axis of rotation, the cylinders of one of said sets being circumferentially staggered with respect to the cylinders of the other of said sets; pistons reciprocable in the cylinders of each set respectively and having outer end portions projecting radially outwardly beyond said cylinder barrel unit; a reactance assembly surrounding said cylinder barrel unit and comprising a middle section and two end sections separably connected to said middle section, said middle section being

formed with a flange extending radially inwardly between the outer end portions of the pistons of said two sets and the inner surface of said flange constituting a middle eccentric track, said end sections being formed with similarly eccentric end tracks; and thrust-transmitting pins respectively individually journaled in the outer end portions of said pistons and extending parallel to said axis of rotation and projecting beyond both sides of the respectively associated piston outer end portions, the pins journaled in the pistons of one set being independent of the pins journaled in the pistons of the other set, the projecting portions of the pins associated with the pistons of one of said sets having independent rolling engagement respectively with said middle track and one of said end tracks, and the projecting portions of the pins associated with the pistons of the other of said sets having rolling engagement respectively with said middle track and the other of said end tracks.

19. In a rotary hydraulic pump or motor, a rotatable cylinder barrel unit comprising two sections adapted to be assembled and separated in a direction longitudinally of the axis of rotation of said unit, and means for maintaining said sections in assembled relation, each section being formed with a set of radial, circumferentially deployed cylinders, the two sets of cylinders being mutually spaced longitudinally of said axis of rotation, the cylinders of one of said sets being circumferentially staggered with respect to the cylinders of the other of said sets; pistons reciprocable in the cylinders of each set respectively and having outer end portions projecting radially outwardly beyond said cylinder barrel unit; a reactance assembly surrounding said cylinder barrel unit and comprising a middle section and two end sections separably connected to said middle section, said middle section being formed with a flange extending radially inwardly between the outer end portions of the pistons of said two sets and the inner surface of said flange constituting a middle eccentric track, said end sections being formed with similarly eccentric end tracks; and thrust-transmitting pins respectively individually journaled in the outer end portions of said pistons and extending parallel to said axis of rotation and projecting beyond both sides of the respectively associated piston outer end portions, the pins journaled in the pistons of one set being independent of the pins journaled in the pistons of the other set, the projecting portions of the pins associated with the

pistons of one of said sets having independent rolling engagement respectively with said middle track and one of said end tracks, and the projecting portions of the pins associated with the pistons of the other of said sets having rolling engagement respectively with said middle track and the other of said end tracks, the pins associated with the pistons of one of said sets axially overlapping and being circumferentially interspaced with the pins associated with the pistons of the other of said sets.

20. In a rotary hydraulic pump or motor, a rotatable cylinder barrel unit comprising two sections adapted to be assembled and separated in a direction longitudinally of the axis of rotation of said unit, means providing a mortise joint between said sections for aligning them, and means for maintaining said sections in assembled relation, each section being formed with a set of radial circumferentially deployed cylinders, the two sets of cylinders being mutually spaced longitudinally of said axis of rotation, the cylinders of one of said sets being circumferentially staggered with respect to the cylinders of the other of said sets; pistons reciprocable in the cylinders of each set respectively and having outer end portions projecting radially outwardly beyond said cylinder barrel unit; a reactance assembly surrounding said cylinder barrel unit and comprising a middle section and two end sections separably connected to said middle section, said middle section being formed with a flange extending radially inwardly between the outer end portions of the pistons of said two sets and the inner surface of said flange constituting a middle eccentric track, said end sections being formed with similarly eccentric end tracks; and thrust-transmitting pins respectively individually journaled in the outer end portions of said pistons and extending parallel to said axis of rotation and projecting beyond both sides of the respectively associated piston outer end portions, the pins journaled in the pistons of one set being independent of the pins journaled in the pistons of the other set, the projecting portions of the pins associated with the pistons of one of said sets having independent rolling engagement respectively with said middle track and one of said end tracks, and the projecting portions of the pins associated with the pistons of the other of said sets having rolling engagement respectively with said middle track and the other of said end tracks.
